SOCKET AND SOCKET INSTALLATION

Scipione M. Del Camp, Maywood, Ill., assignor to
 Cinch Manufacturing Corporation, Chicago, Ill.,
 a corporation of Illinois

Application February 1, 1940, Serial No. 316,794

3 Claims. (Cl. 173—328)

This invention relates to improvements in plug and socket connections, particularly to a connection comprising a socket member of new and original construction adapted to make electrical connection with the leads of a plug member such as an electrolytic capacitor and at the same time providing means electrically engaging a metal shield or envelope provided by the plug member so as to ground the same to another part.

Referring to the drawings, in which I have illustrated a preferred embodiment of my invention:

Fig. 1 is a side elevation of an electrical connection including a socket member secured to a supporting panel with a plug unit such as an electrolytic capacitor in connection with the socket member;

Fig. 2 is a top plan view of a supporting panel with my improved socket member secured thereto;

Fig. 3 is a bottom view of the installation shown in Fig. 2;

Fig. 4 is a sectional view taken along the line 4—4 of Fig. 2 and showing a plug part in electrical connection with the socket member;

Fig. 5 is a sectional view taken along the line 5—5 of Fig. 2 and showing a plug part such as an electrolytic capacitor in partial section;

Fig. 6 is a top plan view of my improved socket member with the uppermost insulating plate removed to show the assembly of the parts;

Fig. 7 is a top plan view of the lowermost insulating plate of the socket member and showing the socket contact terminals assembled therewith;

Fig. 8 is a side elevation of the grounding member forming a part of the socket; and

Fig. 9 is a side elevation of a socket contact terminal carried by the socket member.

Referring to the drawings, I have shown an electrical connection comprising a socket member 1 secured to a supporting panel 2 by attaching means such as the rivets 3 headed over upon opposed sides of the socket member and panel, and a plug unit such as an electrolytic capacitor 4 in electrical connection with the socket member. The socket member 1 carries a plurality of socket contact terminals 5 and a metal grounding member 6 for electrical engagement with a metal envelope of the plug member 4 in a manner to be described. The plug member with which I have chosen to illustrate my improved invention is in the form of an electrolytic capacitor having prong-like terminals 7 extending beyond its lower end for electrical engagement with the

contact terminals 5 of the socket member through an opening 8 of the supporting panel 2. The capacitor, which is preferably similar in form to that illustrated and described in connection with my co-pending United States application, Serial No. 301,625, includes a metal can or envelope 9 having a flange 10 at its lower end. A metal ring member 11 (Fig. 5) and at least one insulating plate 12 are contained within the flange 10. The ring member 11 is maintained in engagement with the metal envelope 9 between the insulating plate 12 and inwardly turned edges 13 (Fig. 5) provided at the outermost end of the flange 10. The prong terminals 7, herein shown as three in number, are secured within the capacitor in any suitable manner and project through the insulating plate 12 beyond the lowermost end of the capacitor. The ring member 11 has an integral pair of guide prongs 14 joined to the ring member around its circumference and extending downwardly beneath the capacitor in the direction taken by the terminals 7 so as to cooperate with the socket member 1 in a way to engage the terminals 7 with proper contacts 5.

The socket member 1 has a body of insulating material which, in my preferred form, is made up of three relatively thin insulating plates including (viewing Figs. 4 and 5) an upper insulating plate 15, a lower insulating plate 16, and an intermediate plate 17. The socket contacts 5, in my preferred form, include a U-shaped terminal-receiving portion comprising side portions 18 and 19 joined by a bight 20. The side portions 18 and 19 are preferably normally in adjacent relation and expandable upon insertion of a prong terminal therebetween to engage opposed sides of the terminal under the tension effected by the bight 20. A support-engaging portion 21 for engagement with the upper surface of the insulating plate 16 extends outwardly from the side portion 19 at its end opposed to the bight 20 and a support-engaging portion 22 extends outwardly from the side portion 18 at its end away from the bight 20 and in a direction opposite to that taken by the support-engaging portion 21. A soldering terminal 23 integrally joined to the portion 22 at its outer end extends downwardly in angular relation thereto.

The lower insulating plate 16 has a number of openings, as most clearly shown in Fig. 7, including three pairs of openings with the openings 24 and 25 of each pair preferably of rectangular form and disposed in spaced parallel relation. The opening 24 of each pair is adapted to receive the side portions 18 and 19 of the

respective contact terminals 5 and the opening 25 receives the soldering terminal 23. Thus the contact terminals 5 are carried by the lower plate 16 with the support-engaging portions 21 and 22 disposed between the insulating plates 15 and 17. The lower plate 16 also has an opening 26 receiving a soldering terminal provided by the metal grounding member 6 and a pair of rectangular openings 27 adapted to receive the guide prongs 14 of the plug member. Each of the openings 27, in my preferred form, has a notch 28 in a longitudinal side thereof for receiving a positioning lug carried by the grounding member 6, as will be described. The intermediate plate 17 provides prong-receiving openings 29 in alignment with the openings 24 of the plate 16. The openings 29 are of predetermined shape to conform to the cross-sectional shape of the prongs 14 adjacent the lower end of the plug member. The plate 17 also has an opening 30 in alignment with the opening 26 and openings 31-31 in alignment with the openings 27 of the plate 16. Each of the openings 31 has a notch 32 in alignment with the notch 28 of the corresponding opening 27.

The grounding member 6 is formed of one piece of sheet metal and comprises a ring-like portion 33 disposed between the plates 17 and 15 when the parts of the socket member are in final assembly. Positioning means in the form of lugs 34-34 integrally joined to the inner peripheral edges of the ring portion 33 extend downwardly therefrom through the aligned notches 32 and 28 of the plates 17 and 16 to maintain the grounding member in fixed relative position. Means for receiving a lead wire (not shown) in the form of a soldering lug 35 extends downwardly from the ring portion 33 through the aligned openings 30 and 26 of the plates 17 and 16 and beyond the plate 16 a sufficient distance to enable a lead wire to be soldered thereto. This lug 35 also may act as the means to position the grounding member in the socket instead of using the lugs 34-34, but I prefer the additional use of the lugs 34-34. A plurality of expandable fingers 36, herein shown as four, integrally joined to the ring portion 33 around the outer peripheral edge thereof, extend upwardly from the ring portion in a direction opposite to that taken by the lugs 34. The finger portions 36 provide inwardly extending portions 37 adjacent their outermost ends with the distance between the innermost points of the portions 37 of opposed fingers 36 less than the diameter of the metal envelope 9 through the flange 10.

The upper plate 15 provides prong-receiving openings 38 (Fig. 2) in alignment with the openings 29 of the plate 17 and openings 39 in alignment with the openings 31 of the plate 17 for receiving the guide prongs 14. The plate 15 also has four openings 40 in relative position to receive the finger portions 36 of the grounding member which extend through the plate 15 to a position above the socket member. The parts of the socket member may be maintained in initial assembly prior to attachment of the socket to the supporting panel 2 through means of a central rivet 41 extending through the insulating plates and headed over on the outer sides of the socket member.

After the socket member has been assembled with the panel 2 and wired permanently into the circuit, the capacitor is connected therewith through moving it toward the socket member in proper relative position to enter the guide prongs

14 into the openings 38 of the upper plate 15. The terminal prongs 1 then may pass through the aligned openings 38 and 29 of the plates 15 and 17 and enter between the sides 18 and 19 of the respective contact terminal 5 to effect electrical connection with the same. During this action the finger portions 36 are expanded by engagement of the flange 10 of the metal envelope therewith and then contract after passage of the flange by the same whereby the inwardly extending portions 37 engage the metal envelope under constant spring tension. Thus the metal envelope may be grounded through the grounding member to a lead wire (not shown) soldered to the terminal 35. The gripping engagement of the fingers 36 with the plug unit also aids to maintain the plug unit in secure mechanical assembly with the socket unit.

Although I have illustrated and described a preferred embodiment of my invention, I do not wish to be limited thereby because the scope of my invention is best defined by the following claims.

I claim:

1. A socket member for an electrical connection including a number of superposed insulating plates, said plates having openings for receiving prong-like terminals of a cooperating plug member and contact springs assembled with said plates in alignment with said openings for electrical engagement with said prong-like terminals, and a metal member including a ring-like portion assembled with said socket between two of said plates, a lug portion integrally joined to said ring-like portion extending downwardly therefrom through one of said plates and cooperating with said plate to maintain said metal member in proper relative position to said socket and to provide a soldering lug, a plurality of yieldable finger portions integrally joined to said ring-like portion around the periphery thereof, said finger portions extending upwardly from said ring-like portion for electrically engaging a shielding envelope of said plug member when said plug and socket members are in connected relation.

2. A socket member for an electrical connection including three superposed insulating plates, the upper and intermediate plates having aligned openings for receiving prong-like terminals, contact springs carried by the lower plate in alignment with said openings for electrical engagement with prong-like terminals of a cooperating plug member, and a metal member assembled with said socket including a ring-like portion disposed between said upper and intermediate plates, said metal member having positioning means cooperating with said plates to maintain said metal member in proper relative position to said socket and a yieldable finger portion integrally joined to said ring-like portion, said finger portion extending from said ring-like portion through said upper plate for electrically engaging a shielding envelope of said plug member when said plug and socket members are in connected relation.

3. A socket member including three superposed insulating plates, the upper and intermediate of said plates having aligned openings for receiving prong-like terminals of a cooperating plug member, contact springs carried by said lower plate in alignment with said openings for electrical engagement with said prong-like terminals, and a member assembled with said socket including a ring-like portion disposed between

said upper and intermediate plates, lug portions integral with said ring-like portion extending therefrom through said intermediate plate and cooperating therewith to maintain said metal member in proper relative position to said socket, 5 a wiring terminal integral with said metal member extending through at least one of said plates,

and a yieldable portion integral with said ring-like portion extending through said upper plate for electrically engaging a shielding envelope of said plug member when said plug and socket members are in connected relation.

SCIPIO M. DEL CAMP.
